SERVER FOR CIGARETTES OR THE LIKE

Julius Ralph Davidson, Chicago, Ill., assignor to
Kensington, Incorporated, New Kensington,
Pa., a corporation of Pennsylvania

Application January 15, 1936, Serial No. 59,242

7 Claims. (Cl. 65—5)

This invention relates to containers adapted to be readily opened to permit the serving of the contents thereof, and more particularly it relates to containers for cigarettes or the like. It is an object of the invention to provide a cigarette container which is easily opened and closed. Another object is to provide such a container in which the opening and closing actions are semi-automatic. Another object is to provide a cigarette container which is simple in construction and compact. In the drawing:

Fig. 1 is an end view of the container constructed according to my invention;

Fig. 2 is a side view of the same container; and
Fig. 3 is a perspective view of the container in a partly open position.

The base 10 has suitably attached thereto the guide pin 11. A connector 12 has holes drilled therein to accommodate the two legs of the guide pin. The guide pin 11 is of a generally inverted U shape when in position and has a reversely bent portion 13 in the bight thereof. In the form shown, the base 10 is provided with beads 14. A handle 15 is attached at points adjacent to its ends to the ends of the connector bar, as by screws, as shown. Two container halves 16 and 17 are pivotally attached to the ends of the handle, as by screws, as shown.

Each of the container halves preferably is substantially semi-cylindrical in shape, and in the preferred form shown in the drawing has a flat wall 18 and a cylindrical wall 19, although, if desired, the flat wall 18 may be omitted so that the container will be completely cylindrical.

The operation of the device is as follows: The container halves are filled with cigarettes or the like, the connector bar 12 and guide pin 11 serving to hold the cigarettes in the container halves when the container is closed. When it is desired to serve cigarettes from the container, the handle 15 is lifted, causing the container halves 16 and 17 to move to open position through the pivotal connections of the handle and the container halves. The cylindrical walls 19 are in contact with suitable bearing surfaces on the base 10 at all times, save in the completely closed position, when the flat walls 18 are in contact with the bearing surfaces. The beads 14 provide these bearing surfaces in the form shown. As the handle continues upwardly, the connector bar 12 strikes the reversely bent portion 13 of the guide pin 11 which is secured to the base, so that the entire container and base may be lifted and carried by the handle, the reversely bent portion 13 serving as a stop to limit movement of the parts

beyond a convenient open position. It will be obvious that so long as the container is carried by the handle the container halves will remain in the open position. The edges of the connector bar 12 extend into the receptacle halves in all positions of the server.

Usually, it is preferred to have the server arranged so that the parts will rest in either the open position or the closed position. For this purpose the weight of the container halves and their associated parts is so arranged that its center will lie between the bearing surfaces on the base when the container is closed and beyond the bearing surfaces when the container is open, allowance being made for variation in the weight of the contents of the container. With this arrangement, it is necessary to lift the handle in order to open the container and to apply a slight, finger-tip pressure on the handle to close the container. It will be obvious that either movement will continue automatically after the center of the weight of the container and its associated parts has passed over the bearing surfaces.

However, if it should be desired that the closing of the container should be completely automatic, this may be accomplished by weighting the handle 15, or the connector bar 12, or by otherwise balancing the parts so that they tend to move to the closed position. In such an arrangement, the center of weight must be, when the container is open, a distance inward from the bearing surfaces sufficient to positively overcome the friction between the cylindrical walls 19 and the bearing surfaces on the base.

Because of its lightness and fabricating properties, I prefer to make the container of aluminum.

Various modifications and adaptations of the structure shown may be adopted without departing from the scope of the invention except as it is defined in the claims.

I claim:

1. A server comprising a base, complementary receptacle halves, an upright member secured to said base, a connector bar slidably mounted on said upright member, a handle secured to the ends of the connector bar and pivotally connected to the receptacle halves, and a stop on said upright member to limit relative movement of the parts.

2. A server comprising a base, complementary receptacle halves resting on said base, an upright member secured to said base, a connector bar slidably mounted on said upright member, a handle secured to the ends of the connector

3. A server comprising a base, complementary receptacle halves each having a cylindrical wall, an upright member secured to said base, a connector bar slidably mounted on said upright member, a handle secured to the ends of the connector bar and pivotally connected to the receptacle halves, and a stop on said upright member to limit relative movement of the parts.
4. A server comprising a base, complementary receptacle halves each having a cylindrical wall bearing on said base, an upright member secured to said base, a connector bar slidably mounted on said upright member, a handle secured to the ends of the connector bar and pivotally connected to the receptacle halves, and a stop on said upright member to limit relative movement of the parts.
5. A server comprising a base, complementary receptacle halves each having a cylindrical wall bearing freely on said base, an upright guide member of substantially inverted U-shape secured at its ends to said base, a connector bar slidably mounted on the legs of said U-shaped member, and a handle member secured adjacent its ends to the ends of the connector bar and pivotally secured at its ends to the receptacle halves, the central portion of said inverted U-shaped member being adapted to bear against the connector bar in the fully open position of the server.
6. A server comprising a base, a substantially U-shaped guide member secured at its ends in an inverted position to the base, a connector bar slidably mounted on the legs of said U-shaped guide member, a handle member of substantially inverted U shape secured adjacent its ends to the ends of the connector bar, and complementary receptacle halves pivotally secured to the ends of the handle member and adapted to lie substantially above the ends of the handle member when the server is in its closed position.
7. A server comprising a base member, bearing surfaces extending above said base member, a substantially U-shaped guide member secured to the base in an inverted position between the bearing surfaces, a handle of substantially inverted U-shape, a connector bar slidably mounted on said U-shaped guide member, said connector bar being attached to the handle adjacent the ends thereof and extending therebetween, and complementary receptacle halves pivotally secured to the ends of the inverted U-handle.

JULIUS RALPH DAVIDSON.
